UNITED STATES PATENT OFFICE.

KNUD MURCK, OF NEW YORK, N. Y., ASSIGNEE TO NEW YORK BLUE PRINT PAPER CO., INC., A CORPORATION OF NEW YORK.

WORKTABLE FOR LITHOPRINTING.

Application filed December 9, 1924. Serial No. 754,719.

To all whom it may concern:

Be it known that I, KNUD MURCK, citizen of the United States, and resident of New York, in the county of New York and State 5 of New York, have invented certain new and useful Improvements in Worktables for Lithoprinting, of which the following is a specification.

This invention relates to the art of litho- 10 printing, and the object of the invention is to provide an improved work and cooling table for making lithoprints.

Lithoprinting is carried on by pouring hot prepared gelatine on a suitable stone on 15 which the gelatine is allowed to cool to form a film thereon. When the gelatine is cold, it receives an imprint from an original tracing or drawing which is to be duplicated. The imprint is thereafter inked and prints are 20 then made from the gelatine, which forms a negative film on the stone. In the industry lithoprints must compete with blue prints and other inexpensive processes of duplication, and it is therefore essential that the 25 lithoprinting process be carried on very rapidly to lower the cost of production. Heretofore this has not been possible to any great extent because of the lack of a proper apparatus for carrying on the process of 30 lithoprinting.

My invention provides a work and cooling table for lithoprinting so arranged that the entire process may be carried out very rapidly and conveniently and whereby the cost of 35 production is materially lower and a practical apparatus is provided for the workman. In the drawing illustrating my invention—

Fig. 1 is a side view of a work and cooling table for lithoprinting embodying my invention with parts removed and parts broken away.

Fig. 2 is an end view of the table.

Fig. 3 is a plan view.

The work table comprises an upper member 5 consisting of a slab of marble or suitable stone with a perfectly level and smooth printing surface 6. The slab 5 rests on a cooling coil consisting of the cooling pipes 7, 8 which are connected to and passed between the two headers 8 and 80. The pipes rest on a wooden table 9.

The stone slab 5 and coil 7 are very heavy and no special means are required to keep 55 them in position on the wooden table. How-

ever, as the table is tilted during the work, suitable clamps 10 are secured to the wooden table to prevent any sliding movement of the stone or the pipes during the work.

The table is mounted on a suitable number 60 of legs or supports 40, 40 which carry bearings 11, 11 in which is mounted a shaft 12. The table is supported and held to the shaft by suitable clamps 13, 13.

At one end the table is provided with a 65 semi circular brace or guide 14 which carries two stops 15 and 16. When the table is tilted to either side, either stop will abut the adjacent table leg 40 and prevent too much tilting. A latch 17 pivoted on the leg 40 70 is adapted to fall by gravity into a notch 18 in the brace 14 to hold the table immovable as is obvious.

At each end of the shaft 12 there is a 75 stuffing box 19 and 20. A pipe 21 leads from the header 8 to the adjacent stuffing box 19 from which another pipe 22 leads to a tank of ice water 23. From the latter there is a pipe 24 leading to a pump 25. A pipe 26 leads from the pump to the stuffing box 20 80 on the other end of the shaft 12. Still another pipe 22 leads from the stuffing box 20 to the header 80. It will thus be seen that when the pump is running, ice water is being pumped from the tank 23, through the 85 headers and cooling pipes and back to the tank. As a consequence, the pipes are ice cold and cool the stone slab 5.

To one side of the table there is provided a trough 27 which is supported on brackets 90 28, which slide in loops 29 under the wooden table. The inner end of the brackets 28 form stops 30. 35 is a counter balancing weight secured to the brace 14.

The operation is as follows:—The table is 95 in normal working position as shown in full lines in Figure 2 in which the table is level and locked by the latch 17 engaging the notch 18. While the table is in this position hot gelatine is poured on the stone slab 5 to 100 cover as much thereof as may be required for a given size print to be made. Or the table may be tilted as shown in the dotted lines in Figure 2 and the gelatine poured on while the table is tilted. While in the latter 105 position the gelatine runs off into the trough 27 which moves out from the table by gravity, but because of the cooled stone slab, sufficient gelatine remains on the stone to form a thin film thereon. If the gelatine is poured 110

on the stone while it is level, the stone is immediately thereafter tilted to cause the surplus gelatine to run off.

The table is then moved back to level position when the latch 17 automatically falls into the notch 18 to lock the table. And of course when the table is tilted the stop 16 limits the movement thereof to the position shown in the dotted lines in Figure 2. 19 Thereafter the imprint is made as aforesaid and inked, and from the gelatine negative thus formed on the stone, duplicate prints are made. When the required number of prints have been made, the gelatine film is 15 scraped off and the table is ready for the next operation.

Because of the counterbalanced table the work in tilting and operating the table requires hardly any effort and the entire process is carried on very rapidly. The pump is kept in constant operation so that the cold water is constantly circulated through the pipes, insuring that the stone slab is at all times sufficiently cool to cause the hot gelatine to settle and form a film almost immediately after it is poured on the stone. It will further be understood that the pipes 21 and 32 are fitted into the stuffing boxes 19 and 20 respectively, so as to turn with the 25 table. Besides the convenience of the apparatus and the rapidity with which the work may be carried on, it is a further advantage that the work may be done in a room at ordinary temperature for the convenience of 30 the workman. Heretofore, it has at times been necessary to carry the stone slab with the hot gelatine thereon into a separate cooling room to settle and then conveyed back

to the workroom. These changes in temperatures caused a great deal of inconvenience 40 to the workmen and loss of time in the operation.

While I have shown my invention in its preferred form, it will nevertheless be understood that changes and modifications may 45 be made in the construction disclosed without departing from the spirit of the invention and the scope of the appended claims.

I claim:—

1. The combination of a stone table adapted to receive hot gelatine for the purpose set forth, means for tilting said stone table to cause the surplus gelatine to run off therefrom, a receptacle for said surplus gelatine automatically operable into receiving position when the said table is tilted, supporting means for said table and means for constantly cooling the said stone table to cause the gelatine to form a film thereon. 55

2. The combination of a balanced stone 60 table adapted to receive hot gelatine poured thereon for lithoprinting purposes, supporting means for said table, mechanism for pivoting said table on the said supporting means, on which said table is adapted to be tilted to cause the surplus gelatine to run off therefrom, a receptacle slidably supported on said table to receive the surplus gelatine therefrom, means for limiting the tilting movement of the table, means for locking 65 the table in working position, pipes placed beneath and in contact with said stone table and means for constantly circulating a cooling medium through the said pipes. 70

KNUD MURCK.
